UNITED STATES PATENT OFFICE.

OLIVER L. DOSCH, OF ELIZABETH, NEW JERSEY, ASSIGNOR TO THE SINGER MANUFACTURING COMPANY, A CORPORATION OF NEW JERSEY.

MACHINE FOR PREPARING RECORD-CARDS.

1,266,230.

Specification of Letters Patent. Patented May 14, 1918.

Application filed October 30, 1915. Serial No. 58,772.

To all whom it may concern:

Be it known that I, OLIVER L. DOSCH, a citizen of the United States, residing at Elizabeth, in the county of Union and State 5 of New Jersey, have invented certain new and useful Improvements in Machines for Preparing Record-Cards, of which the following is a specification, reference being had therein to the accompanying drawings.

10 This invention relates to an improvement in machines for preparing record-cards or other media for the operation of tabulating or sorting apparatus. According to an existing system, means are provided for producing in the cards or other media physical 15 changes in mutually unrelated positions thereon but corresponding individually with quantities or qualities of a predetermined schedule, which is preferably printed upon 20 the cards or other media operated upon.

It has been customary heretofore to apply to the record-cards, in addition to the holes punched therein for coöperation with the tabulating or sorting apparatus, and in 25 a separate operation from the punching action, written or printed data constituting the original record to which the positions of the various punched-out portions correspond under the schedule employed. The 30 present invention has for one of its principal objects to obviate the liability to discrepancy between the two kinds of markings of the record-card or medium involved in the separate and distinct operations by which 35 they are produced.

The invention consists primarily in combining with the means for producing physical changes in the record-card or medium, means for applying thereto in regular order 40 characters corresponding individually with said physical changes, thereby insuring the agreement of the original record data with the physical changes purporting to correspond therewith according to the tabulating 45 or accounting system.

In the preferred form of the present improvement, the machine comprises work-supporting and feeding means in the form of a traveling carrier for the record-cards, 50 with a row of punches arranged crosswise of the direction of travel and a series of type having a common printing point preferably in alinement with the row of punches. Each

punch is connected with and operated by a key and has a connection also with one of 55 the type having a character corresponding with the position of its respective punch of the series, the feeding device having also a connection with each of the operating keys whereby the record card or other medium 60 receives an advance feeding movement for each actuation thereof. In the operation of the keys to produce the original record, which may be effected in either figures or letters, a punched-out hole is invariably produced to correspond in position, according 65 to the schedule employed, with the record character simultaneously applied.

While the physical-change producing means is preferably in the form of a punch 70 for removing a portion of the card or other record-medium, it is evidently immaterial to the present improvement whether the kind of implement employed for effecting this physical change be of the class for removing a portion, as by punching, or adding to the card, as by application of an adhesive disk in a manner in which small labels 75 have been applied to solid objects, or by changes in the surface of the card without 80 removal or addition thereto, as by embossing. It is to be understood that the term "punch," as employed herein, is used for convenience in designating any tool or implement adapted to effect in the card or record- 85 medium a physical change of any of the kinds referred to to adapt it for the operation of the tabulating or sorting apparatus.

The carrier is preferably provided with a clamp for holding securely in position 90 thereon not only the record card to be punched and printed, but one or more additional record sheets with opposed carbon coatings whereby the printed record may be duplicated; but it is obvious that the employment of an ink ribbon passing over the card at the printing point would provide for suitable impressions of the type upon the card in lieu of the employment of carbon-faced paper for the purpose. 95

The invention will be understood by reference to the accompanying drawings, in which Figure 1 is a plan of a record-punching and printing machine embodying the present invention and Fig. 2 is an elevation 105 of the same with the base in section. Figs.

3 and 4 are elevations taken respectively from the opposite ends of the machine and representing certain of the housings in section to expose the parts within. Fig. 5 is an elevation representing the central part of the machine from the opposite side to that represented in Fig. 2, and with certain parts in section. Fig. 6 is a detail partial sectional view representing one of the actuating keys 10 and the parts operated thereby. Fig. 7 is an elevation representing one of the keys from a different viewpoint and the connection with its respective type-carrying bar. Figs. 8 and 9 are respectively a sectional elevation and a plan of different parts of the feeding mechanism. Figs. 10 and 11 are views of the opposite faces of a portion of a duplication sheet, showing bands of carbon coating applied thereto. Fig. 12 is a transverse section representing a record-card with an overlying duplication sheet folded to produce several copies of the printed record.

In its capacity as a record-card punching machine, the machine represented in the accompanying drawings is similar in general constructive features to that forming the subject of the United States patent to Herman Hollerith, No. 682,197, of September 10, 1901. It is constructed with the hollow 25 rectangular base 1 supporting the bed-plate 2 which is formed with a longitudinal slot 3 in which the work-carrier or card-holder travels.

The work-carrier comprises the bar 4 formed upon its lower edge with the rack-teeth 5 and at the opposite ends of its upper edge with the raised seats 6 and 7. Upon the seat 6 is secured a plate 8 having lateral guide-wings 9 entering guide-grooves 10 in the adjacent edges of the bed-plate sections 2 at opposite sides of the slot 3. The plate 8 has upon one end the block 11, a portion of whose top affords one jaw of a gripping device or clamp of which the other jaw is afforded by lateral extension 12 of an upwardly and laterally extending lever 13 hinged to the block 11 by means of the pin 14. The clamp is maintained normally closed upon the card or other article, as represented in full lines in Fig. 2, by means of a spring 15 secured upon the back of the lever and having its free end resting against the block.

Upon the seat 7 is secured the plate 16 provided with lateral wings 17 entering the guide-grooves 10 and provided with an upwardly extending stop-lug 18 for the end of the record-card opposite that gripped by the clamp 11 12.

The teeth 5 of the rack-bar 4 are in mesh with the pinion 19 which is journaled upon the stud 20 tapped into an extension 21 of the bearing bracket 22 which is sustained by the bearing boss 23 projecting inwardly from the frame-plate 24, which plate is in turn

secured by screws 25 to the outer face of the lateral extension 26 of the base 1. Journaled within the bearing boss 23 is the shaft 27 having fixed upon one end the pinion 28 meshing with the pinion 19 and upon the opposite end the pinion 29 in mesh with the peripheral spur-teeth 30 of a disk 31 having also upon its periphery the ratchet-teeth 32 adjacent the spur-teeth.

The toothed disk or wheel 31 has a boss 33 which is journaled upon the stud 34 extending from the frame plate 24 and is formed in its outer face with a central recess having a pocket in its outer periphery to receive the eyed outer extremity 35 of a spring 36 formed with a similar inner extremity 37 which enters a peripheral notch in a thimble 38 embracing the outer portion of the hub 33 of the toothed wheel and apertured and shouldered to fit the reduced outer portion of the stud 34 upon which it is frictionally clamped by the head of the screw 39 tapped into the outer end of the stud 34 (Fig. 8). By temporarily loosening the screw 39, the thimble may be turned to wind up the spring for subjecting the wheel 31 to the desired degree of tension in propelling the work-carrier through its described connections with the rack-bar 4.

Journaled in a suitable bearing boss 24' of the frame-plate 24 is a rock-shaft 40 having loosely journaled thereon a plural-armed lever comprising the downwardly extending pawl-arm 41 having at its extremity a tooth 42 adapted for engagement with the peripheral ratchet teeth of the wheel 31 and a lateral arm 43 having its extremity connected by means of the spring 44 with a pin 45 upon the rock-shaft 40. As represented in Fig. 1, the hub of the plural-armed lever is formed with a clearance notch loosely embracing the pin 45 and affording a shoulder which is pressed yieldingly against the pin under the action of the spring 44.

The rock-shaft has also loosely journaled upon its outer end and confined thereon by the cross-pin 46 the hub 47 of a holding pawl-lever 48 provided at its free end with the tooth 49 normally maintained in operative engagement with the ratchet toothed periphery of the wheel 31 by a spring 50 connecting the lever 48 with a pin 51 upon the frame-plate 24. The lever 48 has an aperture 48' which is entered by a lateral pin 52 upon the lever-arm 43.

In the normal position of the rock-shaft 40, the pawl-tooth 42 is maintained normally out of engagement with the ratchet-teeth of the wheel 31, but when the rock-shaft is actuated for a feeding action, such pawl is moved into engagement with the ratchet-toothed periphery of the disk 31 and the holding lever 48 is retracted by engagement of the upper side of the aperture 48' with the lifting pin 52, the parts resuming normal

position, as represented in Fig 5, when the rock-shaft is released by its actuating means. The spring cavity of the wheel 31 is closed by the annular cover-plate 53 upon which is secured the guard-ring 54 projecting beyond the periphery of the wheel 31 to confine the pawl-teeth 42 and 49 in operative relation with the ratchet-teeth 32.

Journaled in the plate 24 is a rocking pin 55 bent laterally from one end of the pawl-lifting lever 56 provided with the button or key 57. The pin 55 is formed in its outer end with a fork in which is secured the pawl-lifting plate 58 normally resting upon the stop-pin 59 under the action of a spring 60 connected at one end with said pawl-lifting plate and at the opposite end with a pin 61 upon the frame-plate 24. The plate 58 normally lies below the outer extremity of the pawl-lever 48, as represented in Fig. 5, so that such lever normally works independently thereof, but upon depression of the lifting lever 56 the plate 58 engages the pawl-lever 48 and lifts its tooth 49 clear of the ratchet-teeth of the wheel 31, the aperture 48' being sufficiently large to permit the lifting of the lever 48 without action upon the pin 52 to throw the pawl-tooth 42 into engagement with the ratchet-teeth. The lifting movement of the plate 58 is limited by the stop-pin 62.

As will be observed, the pawl-levers 41 and 48 together form an escapement in conjunction with the peripheral ratchet-teeth 32 of the wheel 31 to control the step-by-step rotation of the pinion 29, and hence the travel of the work-holder, under the action of the spring 36. The actuation of the pawl-lifting lever 56 obviously serves to free the wheel 31 of the control of both pawl-elements of the escapement so as to permit the work-carrier to move freely under the action of the spring 36 to initial position upon the machine frame, wherein the end of the rack-bar engages the adjustable carrier-stop 63.

Secured upon the bed-plate 2 is a frame comprising the upright members 64 and the spaced cross-members 65. Journaled in a suitable bearing of said frame is a rocking pin 66 arranged in alinement with the rock-shaft 40 and provided with a crank-arm 67 between which and a similar crank-arm 68 loosely mounted upon the rock-shaft 40 is a transverse universal bar 69 the depression of which causes the rocking of the shaft 40 for actuation of the feed-escapement.

An extension of the bar 69 carries an adjustable screw-pin 70 whose point rests upon a lateral arm 71 projecting from a collar 72 fixed upon the rock-shaft 40 and bearing upon the head of a pin 73 journaled in a socket of an extension of the frame-plate 24 and normally pressed upwardly by a spring 74 (Fig. 3), thereby providing for maintenance of the rock-shaft in initial position.

Journaled within one of the frame-members 65 are the punches 75 arranged in a row transverse to the direction of travel of the work-carrier and having their reduced lower portions 76 fitted to corresponding apertures 70 in the transverse guide-bar 77 between which and the enlarged portions 75 of the punches are interposed the lifting springs 78. The reduced operative end portions of the punches work in suitable apertures 79 of the transverse die-plate 80 whose upper face is substantially at the level of the upper work-supporting face of the bed-plate 2 (Figs. 2 and 6).

One of the frame-members 65 sustains a row of depending fulcrum screw-pins 81 each having a rounded lower extremity entering a pocket formed in the upper edge and at one end of a bent punch-lever 82 (Fig. 2) whose opposite end is formed with a fork 83. The fork 83 embraces the reduced portion of a push-rod 84 journaled in the frame-member 65 and formed with a lateral notch 85 to receive one member of the fork. Each push-rod is provided upon its upper end with a key 86.

Each of the punch-levers 82 near its fulcrum-pin 81 rests upon the top of a punch 75 intermediate which and its respective push-rod 84 it is adapted for engagement 95 with the universal bar 69 (Fig. 6). The push-rods 84 are for convenience arranged in several rows crosswise of the direction of feed. It is obvious that the depression of a key 86 acts through the lever 82 to actuate 100 its respective punch and to simultaneously engage the universal bar 69 to operate the escapement for producing a feed step.

Each of the push-bars 84 is formed in its lower end with a lateral notch affording a 105 shoulder 87 for engagement by one of the members of a forked arm 88 embracing the reduced lower end of the push-bar and having its hub 89 secured by means of a set-screw 90 upon one of a series of type-bar 110 rock-shafts 91 suitably journaled in the frame-members 64. Each rock-shaft 91 has fixed upon one end a type-bar 92 more or less laterally offset at its outer or free end upon which is mounted a type-block 93 having a printing face formed with a suitable character which is preferably a figure, but which may be a letter of the alphabet.

The type-bars are of such proportion and shape that in the rocking of their respective 120 shafts by the described connection with the push-rods 84 their respective types will descend upon the object to be printed through an aperture 94 formed in the guide-bar 77 preferably in alinement with the punches 125 75, 76 (Fig. 2). The type-bar rock-shafts 91 are surrounded each by a spring 95 having one end attached to the set-screw 90 and the other end connected to an adjacent rock-shaft or to a stud-pin 96 (Fig. 3), these 130.

springs serving to maintain the type-bars 92 in upright position wherein their type-carrying ends rest against the yielding facing 97 of an upwardly extending arm 98 rigidly attached to one of the frame-members 64 by means of the screws 99. Secured upon the machine bed by means of a screw 100 is a flat buffer-spring 101 slightly inclined above the face of the bed-plate and extending toward the printing aperture 94. This spring serves as a buffer to produce a quick recoil of the type after a printing impact.

Journalized in a bearing 65' of the frame is a push-rod 84' provided at its upper end with a button 86 and having its laterally notched lower end embraced by the fork 102 of a spacing lever 103 loosely journalized upon the stud-screw 104 depending from one of the frame-members 65 (Figs. 3 and 5). The lower edge of the lever 103 rests upon the universal bar 69 and may be actuated by depressing the push-rod 84' to rock the shaft 40 and thereby effect the advance of the work-carrier without the actuation of the punching and printing elements.

Arranged over the bed-plate sections 2 upon opposite sides of the slot 3 intermediate the guide-bar 77 and the end of the bed-plate adjacent the stop 63 are the flat shield-plates 105 which are secured upon the bed-plate by means of screws 106 with interposed washers 107 (Figs. 1 and 3). The bed-plate is formed upon its opposite edges with the standing guide-ribs 2' for guiding the edges of the record-card 108 beneath the punching and printing implements, the advance edge of the card being directed downwardly upon the bed-plate by means of the upwardly inclined fingers 109 extending from one edge of the guide-bar 77.

The manifold- or duplication-sheet 110 is provided on its face near one edge with a longitudinally extending band 111 of carbon coating (Fig. 10) and upon its back with two similar bands 112 and 113 (Fig. 11).

To prepare this sheet for insertion in the machine, the marginal portion is folded upon the body portion along the line of perforations 114 from left to right (Fig. 10) to form a fold 110' and then reversely upon a line at the opposite edge of the carbon-band 111 to form a superposed fold 110'', as represented in Fig. 12, the carbon-band 113 resting upon the margin of the upper face of the record-card 108, and the carbon-coated faces of the flaps 110' and 110'' being presented in the same direction. As thus folded, the duplication sheet is designed to correspond substantially in length and width with the record-card 108 and both are inserted in the holder in the relation represented in Fig. 12 with one end resting against the stop-lug 18 and the other end

resting upon the lower clamping jaw of the block 11 upon which it is clamped by means of the spring-pressed upper jaw 12, as represented in Fig. 2.

As will be observed, the carbon-coated portions of the sheet 110 when in operative position overlie the margin of the record-card at the head of the several columns of figures, and in the operation of the machine the depression of the several keys in the proper order effects the printing of the original record in the characters formed upon the type at the printing point at the end of the line of punches which latter pass through the body of the duplication sheet 80 and through the record-card to punch out numbers or characters previously printed upon the record-card corresponding in position and value with the printing characters with which they are respectively connected through the operating keys. In the described arrangement of the carbon coated portions of the sheet 110, impressions of the record are made upon the blank upper faces of the flap 110' and the marginal portion of the body of the sheet, and also upon the margin of the record-card beneath the same. At the completion of the record producing operation, the clamp-lever 13 is tilted (as represented in dotted lines in Fig. 2) to 95 release the record-sheets which are removed and the folded marginal portion of the sheet 110 detached at the line of perforation 114, thereby producing three facsimile records for distribution in different record 100 departments or bureaus, the perforated record-card 108 being the one employed in the subsequent tabulating operation in connection with appropriate apparatus.

The duplication sheet 110 is preferably made of such width that, when folded as described, it will be loosely embraced by the guide-ribs 2' of the bed-plate 2 to insure its maintaining proper relation with the record-card in the printing and punching 110 operation, but it is evident that this sheet will perform its proper function if made narrower, with suitable provision for holding it in register with the printing elements and the record-card 108.

That portion of the feeding mechanism disposed outside of the body of the machine frame is preferably inclosed within a detachable housing 115 secured to the frame plate 24 by means of screws 116 (Fig. 1). 120 To shield the type-bars from disarrangement or injury, a segmental box or housing 117 may be secured upon the frame by means of fastening screws 118 so as to entirely inclose the parts of the printing mechanism 125 exterior to the machine frame.

From the foregoing description it is evident that the present improvement may be embodied in widely different forms of mechanism for producing record-cards or other 130

media such as those herein described, and that the specific mechanism disclosed herein is not therefore material to the present invention.

5 Having thus set forth the nature of the invention, what I claim herein is:—

1. In a machine of the class described, work-supporting and feeding means, a plurality of movably mounted punch elements 10 adapted to perforate the work, a plurality of printing type mounted to print upon the perforated work, a plurality of push-rods, connections between each push-rod and each of said type, respectively, and a single lever- 15 connection between each push-rod and a corresponding one of said punch-elements.

2. In a machine of the class described, work-supporting and feeding means, a plurality of punch-elements adapted to perforate 20 the work, a plurality of printing type mounted to print upon the perforated work, a plurality of push-rods, a single jointed connection between each push-rod, and each of said type, respectively, and a single lever- 25 connection between each push-rod and a corresponding one of said punches.

3. In a machine of the class described, work-supporting and feeding means, a plurality of punches disposed on one side of 30 said work-support and adapted to perforate the work, a plurality of printing type mounted to print upon the perforated work on the same side as said punches, and a plurality of keys connected to actuate each of 35 said punches and its corresponding printing type at substantially the same time.

4. In a machine of the class described, work-supporting and feeding means, a plurality of punches arranged substantially in 40 a common plane and adapted to perforate the work, a plurality of type-bars pivoted to swing about axes substantially parallel with said plane to print upon said perforated work, a plurality of actuating keys, 45 and connections between each of said keys and its corresponding punch and type-bar.

5. In a machine of the class described, in combination, a frame card-supporting and feeding mechanism, card perforating mechanism 50 including a series of punches disposed above said first mentioned mechanism and substantially in a plane extending transversely of the direction of feed, card-printing mechanism carried by said frame and disposed above said card-supporting and feeding mechanism and including a series of movably mounted printing type adapted to print at a common printing point relatively to said frame upon the card 55 being punched, and a series of actuating keys each adapted to simultaneously actuate a corresponding punch and printing type.

6. In a machine of the class described, in combination, a series of punches adapted to 60 perforate the work, a series of parallel push-

rods, actuating connections between each of said punches and its corresponding push-rod, a series of parallel shafts disposed transversely of and operatively connected each to its corresponding push-rod, and a 70 series of type-bars each carried by a corresponding one of said shafts, and so disposed as to print upon the work being perforated.

7. In a machine of the class described, a 75 series of vertically disposed punches adapted to perforate the work, a series of type-bars pivoted upon horizontal axes to print upon the work being perforated, a series of actuating keys, and operative connections between each of said keys and its 80 corresponding punch and type-bar.

8. In a machine of the class described, a series of vertically disposed punches adapted to perforate the work, a series of type-bars pivoted upon parallel horizontal axes 85 to print upon the work being perforated, a series of actuating keys, and operative connections between each of said keys and its corresponding punch and type-bar.

9. In a machine of the class described, 90 work-supporting and feeding means, a plurality of elements for producing physical change in a record-card, a plurality of marking elements each adapted to apply to the card a character corresponding with an 95 appropriate one of the first-named elements, a plurality of push-rods formed with thrust shoulders, levers each affording a connection between one of the first-named punches and a shoulder of its respective push-rod, rock- 100 shafts each operatively connected with one of the second-named elements, and a connection between another shoulder of each of said push-rods and its respective rock-shaft for insuring the simultaneous operation of 105 the first-named element with the corresponding one of the second-named elements.

10. In a machine of the class described, work-supporting and feeding means, a plurality of elements for producing physical 110 change in a record-card, a plurality of marking elements each adapted to apply to the card a character corresponding with an appropriate one of the first-named elements, a plurality of push-rods each formed with a 115 lateral notch, levers each formed with a fork embracing and entering one of the notches of a push-rod and operatively connected with one of the first-named elements, rock-shafts each sustaining one of the second-named elements, and a forked arm fixed upon each of said rock-shafts and embracing and entering another notch in its respective push-rod.

11. In a card-punching machine, in combination, a frame, a traveling work-support, a plurality of reciprocatory punches journaled in said frame to perforate the work, a plurality of rock-shafts also journaled in said frame, type-bars each fixed upon its 120 125 130

5
12. In a card-punching machine, in combination, a frame, a traveling work-support, a plurality of reciprocating and spring-retracted punches journaled in said frame, a plurality of rock shafts also journaled in said frame, a plurality of type-bars each fixed upon its respective rock-shaft, types upon said bars adapted for operation in a common printing point, type-bar retracting springs applied to said rock-shafts, a plurality of push-rods, punch-levers each affording an operative connection between one of said punches and a push-rod, and crank-arms upon said rock-shafts each affording an operative connection between its respective rock-shaft and one of said push-rods.

10
15
20
25
30
35
13. In a card-punching machine, in combination, a frame, a traveling work-support, a plurality of reciprocating punches journaled in said frame, a plurality of rock shafts also journaled in said frame, type-bars each fixed upon its respective rock-shaft, types upon said bars adapted for operation in a common printing point, actuating means operatively connected with each punch and the rock-shaft of a corresponding type-bar for effecting their simultaneous operation, and a buffer-spring sustained by

said frame adjacent the printing point and adapted for engagement by said type-bars.

14. In a machine of the class described, a work-support, a clamp thereon adapted to secure together and to the work-support a plurality of superposed record media, a plurality of elements adapted for action upon one of said superposed media for producing physical change therein, a plurality of marking elements each adapted to impress upon all of said media a character corresponding with an appropriate one of the first-named elements, and feeding mechanism for imparting step-by-step advance movements to said work-support relatively to both sets of elements.

15. In a machine of the class described, a work-support, a plurality of punching elements adapted to perforate the work, a plurality of marking elements adapted to mark the work being perforated, feeding means connected with said work-support, actuating means operatively connected with both sets of elements and with said feeding means for producing the independent operation of said punching elements each with a corresponding marking element and for effecting a feed of the work-support in conjunction with the punching and marking actions on the work, and means connected with the feeding mechanism for imparting to the work-support a feed-step independently of the punching and marking elements.

In testimony whereof, I have signed my name to this specification.

OLIVER L. DOSCH.
